(57) **CLAIM**

The ornamental design of a virtual reality (VR) headset add-on, as shown and described.

DESCRIPTION

FIG. 1 is a top perspective view of a virtual reality (VR) headset add-on with an attached VR headset according to an embodiment of the invention;

FIG. 2 is a top perspective view of a VR headset add-on according to an embodiment of the invention;

FIG. 3 is a front view of a VR headset add-on according to an embodiment of the invention;

FIG. 4 is a rear view of a VR headset add-on according to an embodiment of the invention;

FIG. 5 is a (right) side view of a VR headset add-on according to an embodiment of the invention;

FIG. 6 is a (left) side view of a VR headset add-on according to an embodiment of the invention;

FIG. 7 is a top view of a VR headset add-on according to an embodiment of the invention;

FIG. 8 is a bottom view of a VR headset add-on according to an embodiment of the invention;

FIG. 9 is a front view of a display of the VR headset add-on according to an embodiment of the invention; and,

FIG. 10 is a side view of a display of the VR headset add-on according to an embodiment of the invention.

The dashed broken lines in the figures, such as those depicting a VR headset, form no part of the claimed design.
